UNITED STATES PATENT OFFICE

ROBERT R. ROBERTSON, OF CHICAGO, ILLINOIS

EXPANSION JOINT

Application filed January 5, 1931. Serial No. 506,510.

This invention relates to an expansion joint for use in concrete construction work, such as roads and the like, and, with said joint being constructed with a substantial 5 base adapted to be partly embedded in the sub-grade and having the upper surfaces thereof coated with a material permitting slideable movement of concrete road sections with respect thereto, said base having a hole 10 low web thereon for the reception of retaining stakes and for an inner cap and a mould cap to facilitate forming a groove in the body of the road for the reception of asphaltum or the like above the inner cap 15 after removal of the mould cap from the web.

It is an object of this invention to provide an expansion joint wherein a base is provided with a hollow spring web having a spring cap engaged therein beneath a removable mould cap to support an expansion joint filling thereon after concrete has been poured and the mould cap has been removed.

It is also an object of this invention to provide an expansion joint adapted to be 25 staked in position on a road sub-grade and having the supporting section thereof coated with grease or a similar material to facilitate slideable movements of the concrete road sections thereover when contraction or expansion takes place.

It is a further object of this invention to provide a concrete road expansion joint wherein a hollow flexible web having inner and outer caps supported therein to enclose 35 retaining stakes which project through the hollow web and through an arched base the upper surfaces of which are coated with a lubricant which serves to prevent adherence of the concrete to the base to allow for movement of the concrete sections over the base resulting from the expansion or contraction of the concrete due to temperature changes.

It is an important object of this invention to provide a concrete road expansion joint of 45 simplified and inexpensive construction provided with a greased base and a web consisting of flexible spaced walls to permit retaining stakes to project therebetween and through an arched flexible inner cap supported by the web beneath a removable

mould cap, which after concrete has been poured and allowed to partially set is removed to permit a filling of expansible material to be deposited in the groove and supported upon the inner cap so that the filling is maintained in position when the web forming walls are moved toward or away from one another due to temperature changes.

Other and further important objects will be apparent from the disclosures in the accompanying drawing and the specification.

The invention (in a preferred form) is illustrated in the drawing and hereinafter more fully described.

On the drawing:

Figure 1 is a fragmentary vertical section through a concrete road having embedded therein an improved expansion joint embodying the principles of this invention, and illustrating a filling of expansible material above 70 the inner cap replacing the removed mould cap.

Figure 2 is an enlarged fragmentary vertical section of the expansion joint embedded in concrete with the removable mould cap 75 still in position.

Figure 3 is a fragmentary detail section taken on line III—III of Figure 2.

Figure 4 is a transverse vertical section of a modified form of expansion joint.

Figure 5 is an enlarged fragmentary horizontal detail view taken on line IV—IV of Figure 4 with the mould cap omitted.

As shown on the drawing:

The reference numeral 1 indicates a concrete road sub-grade having supported thereon an expansion joint comprising a comparatively heavy metal base 2, having the longitudinal margin thereof bent downwardly to afford rounded flanges 3 producing an arched base which, when in use, is adapted to be pressed down into the sub-grade with the top surface of the base plate 2 substantially flush with the top surface of the road sub-grade.

Applied to the upper surface of the base is a coating of grease 4 or any other suitable slippery substance which will serve to prevent the adherence of concrete to the base to permit the concrete sections 5 forming the upper portion of the road, to slidably move over the

base when said sections are moved by the contraction or expansion of the concrete resulting from temperature changes.

Secured longitudinally, by means of rivets 6 or other suitable means upon the top of the base plate 2 is a web constructed of comparatively thin light weight sheet metal in the form of a U-shaped body comprising a base 7 which connects a pair of upright flexible walls or plates 8. The web is thus of hollow construction having the upper margins of the side walls 8 bent outwardly and upwardly to form a channel head 9.

Sprung into seated engagement with the channel head 9 is an inner arched cap 10 which fits against the side flanges of the head 9 and serves as a cover to close the chamber formed between the web walls 8.

The inner cap 10, the bottom plate 7 of the web and the base plate 2 are all provided with apertures or openings for the reception of retaining stakes or pins 11 which are inserted to project downwardly through the inner cap 10, through the web chamber and base 7 and through the openings in the base plate 2, to be driven into the sub-grade 1 to hold the expansion joint staked in a selected position upon the sub-grade.

The inner cap 10 and the upper ends of the stakes 11 are enclosed by means of a removable mould cap 12 having concave side flanges which engage the web channel head 9 to hold the top of the mould cap at an elevation to correspond to the top surface of the road when complete.

With the expansion joint positioned upon the sub-grade 1 as described, concrete is poured upon the sub-grade to embed the expansion joint producing the road sections 5. The grease coating 4 applied to the top surface of the base plate 2 prevents the concrete from adhering to the base of the expansion joint. After the concrete has been tamped and leveled, it is permitted to set a required amount after which the mould cap 12 is removed leaving a channel or groove bounded by rounded side walls. The groove is filled with asphaltum or pitch which fillings is supported upon the arched inner cap 10 to form an expansion strip 13.

Figures 4 and 5 illustrate a modified form of expansion joint comprising an arched metal base 14 provided with stake apertures or openings. The upper surface of the base 14 is covered with a coating of grease 15 or the like to prevent the adherence of concrete to said base and permitting the concrete sections in which the expansion joint is embedded to have relative sliding engagement over the base 14 when the concrete sections are expanded or contracted due to temperature changes.

Riveted or otherwise secured upon the top of the base 14 are the lower flanges 16 of a pair of spaced web forming walls or plates 17.

The upper margins of the walls 17 are bent outwardly and upwardly to form an upper channel head 18. Sprung or frictionally seated in the channel head 18 is an apertured arched inner cap 19 which serves as a cover to close the upper end of the chamber formed between the web side walls 17.

Projecting through the openings 20 in the inner cap 19 and downwardly between the web walls 17 are retaining stakes or pins 21, which project through openings in the base 14 and are driven into the road sub-grade to hold the expansion joint staked in position.

The inner cap 19 and the upper ends of the stakes 21 are enclosed by means of a removable mould cap 22 which is left in position until after the concrete is poured and has set. The mould cap is then removed to leave an expansion groove in the concrete which is then filled with a filling of asphaltum or pith to form an expansion strip 13 which rests upon the inner cap which is permitted to expand and contract as the web walls 17 are moved away or toward one another due to contraction or expansion of the concrete sections between which the expansion joint is positioned.

It will be noted that an expansion joint has been devised having a sufficiently heavy greased base supporting a hollow, light metal web for supporting an arched flexible inner cap. The retaining stakes are enclosed between the web walls, thereby affording an arrangement permitting the web walls to be moved toward or away from one another allowing the inner cap to be compressed or expanded to keep the top of the web chamber closed when expansion or contraction of the concrete sections occurs due to temperature changes.

When mounted in position, the base of the expansion joint is sunk or pressed into the sub-grade permitting the greased surface of the base to be so positioned that a sliding movement of the concrete sections adjacent the sides of the web may readily take place over said base when temperature changes cause expansion or contraction of the concrete.

It will, of course, be understood that various details of construction may be varied through a wide range without departing from the principles of this invention, and it is therefore, not the purpose to limit the patent granted hereon otherwise than necessitated by the scope of the appended claims.

I claim as my invention:

1. An expansion joint comprising an apertured base, a hollow web secured thereon, a channel formed on said hollow web, an apertured arched cap seated in said channel, staking members projecting through said apertured arched cap, said hollow web and through said base to secure the expansion joint in position, and a removable mould cap

supported by said channel to enclose said cap.

2. An expansion joint comprising an arched base, a hollow web supported thereon, an inner cap seated in said hollow web, and an outer mould cap removably supported over said inner cap.

3. An expansion joint comprising an arched base, a hollow web supported thereon, an expansible and contractible inner cap seated in said hollow web, staking members projecting through said inner cap, said hollow web and said base, and a mould cap removably engaged on said hollow web to enclose the inner cap, and the upper ends of said staking members.

4. An expansion joint comprising a base, a web thereon, means for staking the expansion joint in position, and inner and outer caps supported on said web.

5. An expansion joint comprising a base, a web secured thereon, a coating of grease on said base, an expansible and contractible inner cap seated in said web, staking members projecting through said inner cap, said web and said base to hold the expansion joint secured in position, and an outer cap removably engaged on said web to enclose the inner cap.

30 6. An expansion joint comprising an apertured flanged base, a hollow web secured longitudinally thereon, a channel formed on the upper end of said web, an arched apertured inner cap seated in said channel, staking members projecting through said inner cap, said hollow web and through said apertured base, an outer mould cap engaged with said channel to enclose the inner cap, said flanged base having a coating of grease thereon to facilitate movement of concrete sections thereover when the expansion joint is embedded in a concrete structure.

45 7. An expansion joint comprising a pair of spaced walls, a support therefore, and an arched spring closure sprung between said walls to form a flexible support for an expansible material, said flexible support adapted to be adjusted to variable widths depending upon variations in the spacing of said walls.

50 8. An expansion joint comprising a pair of spaced resilient walls, means between said walls for supporting the same in position, and an expansible and contractible spring closure supported by said walls for supporting an expansible material above the expansion joint.

In testimony whereof I have hereunto subscribed my name at Chicago, Cook County, Illinois.

ROBERT R. ROBERTSON.
